UNITED STATES PATENT OFFICE

108,436

DESIGN FOR A FEEDING TROUGH

Ney Gwilt, Gridley, Calif.

Application December 21, 1937, Serial No. 73,787

Term of patent 3½ years

To all whom it may concern:

Be it known that I, Ney Gwilt, a citizen of the United States, residing at Gridley, in the county of Butte and State of California, have invented a new, original, and ornamental Design for a Feeding Trough, of which the following is a specification, reference being had to the accompanying drawing, forming part thereof.

The drawing is a perspective view of a feeding trough showing my new design.

I claim:—

The ornamental design for a feeding trough, as shown.

NEY GWILT.
